FOREIGN PATENT DOCUMENTS

CN 305766377 * 5/2020

Primary Examiner — Paula Allen Greene(74) *Attorney, Agent, or Firm* — Hamre, Schumann, Mueller & Larson, P.C.**CLAIM**

The ornamental design for headphone storage case as shown and described.

DESCRIPTION

FIG. 1 is a front planar view of a headphone storage case in closed position;

FIG. 2 is a bottom planar view of FIG. 1 thereof;

FIG. 3 is a top planar view of FIG. 1 thereof;

FIG. 4 is a right side planar view of FIG. 1 thereof;

FIG. 5 is a left side planar view of FIG. 1 thereof;

FIG. 6 is a back planar view of FIG. 1 thereof; and,

FIG. 7 is a perspective view of FIG. 1 thereof.

The features shown in broken lines depict environmental subject matter only and form no part of the claimed design.
